PAGE 3

FIGURE 1 is a side elevational view of a trailer showing my new design;

FIGURE 2 is an elevational view of the opposite side thereof;

FIGURE 3 is a front elevational view thereof;

FIGURE 4 is a rear elevational view thereof;

FIGURE 5 is a top plan view thereof;

FIGURE 6 is a side elevational view showing the trailer in extended position;

FIGURE 7 is an elevation of the opposite side thereof;

FIGURE 8 is a front elevational view thereof;

FIGURE 9 is a rear elevational view thereof; and

FIGURE 10 is a top plan view thereof.

I claim:

The ornamental design for a trailer, as shown and described.
